UNITED STATES PATENT OFFICE.

FRANÇOIS BAVEREY, OF LYON, FRANCE, ASSIGNOR TO SOCIETE DU CARBURATEUR ZENITH, OF LYON, FRANCE, A CORPORATION OF FRANCE.

CARBURETOR.

Application filed September 24, 1920. Serial No. 412,426.

To all whom it may concern:

Be it known that I, FRANÇOIS BAVEREY, a citizen of the French Republic, residing at Lyon, in France, have invented a new and useful Improvement in Carburetors, of which the following is a full, clear, and exact description.

The present invention relates broadly to carburetors, and more particularly to carburetors having an easily regulable idling and starting mixture.

The principal object of the present invention is to provide a carburetor having means permitting accurate proportioning of the slow speed running or idling mixture, and temporary enrichment of such mixture for starting purposes.

A further object of the present invention is to provide an attachment for the atmospheric wells of carburetors by means of which the idling or slow speed jet fed thereby may be caused to supply a combustible mixture having a greater quantity of fuel in proportion to the air, without varying the supply of air to the atmospheric well.

The foregoing and other objects, together with their attendant advantages, will be apparent as the invention becomes better understood, by reference to the accompanying specification and drawings forming a part thereof, it being premised that changes may be made in the various details and the manner of operation, within the scope of the appended claims, without departing from the spirit of the invention.

Figure 1 is a diagrammatic view of a construction in accordance with the present invention.

Figure 2 is a similar view of a slightly modified embodiment of my invention.

Figure 3 is a vertical sectional view through an atmospheric well having my improved regulating device applied thereto.

Figure 4 is a side elevation of the construction illustrated in Figure 3 removed from the well.

Figure 5 is a view, corresponding to Figure 3, of a slightly modified form of my invention.

Figure 6 is a view, corresponding to Fig-

ure 4, of the modification illustrated in Figure 5.

Figure 7 is a detail sectional view on an enlarged scale of the adjustin^o valve, and

Figure 8 is a vertical sectional view 55 through a commercial carburetor constructed in accordance with my invention.

In my earlier Patent No. 1,186,371, of June 6, 1916, there is disclosed an improvement in adjusting devices for carburetors 60 comprising means for varying the amount of air to the main well. My present invention has relation generally to a construction of this nature but differing therefrom in that the supply of air to the main well is not 65 changed and only the slow speed mixture made richer to facilitate starting.

Referring more particularly to the drawings, there is illustrated a carburetor comprising a constant level chamber 1 having a 70 suitable connection to a main feed jet 2 terminating adjacent the point of maximum restriction in the venturi 3 of the suction pipe 4. Surrounding the main jet 2 is a compensating jet 5 receiving its supply of 75 fuel from an atmospheric well 6 having an air opening 7 to the atmosphere. The suction pipe 4 has the usual air inlet 8 and is controlled by a suitable throttle valve 9. In general, the details of construction, as de- 80 scribed, are shown in my Patent 1,188,390, of June 27, 1916.

In the embodiment of my invention illustrated in Figure 1, the atmospheric well 6 has extending thereto a tube 10 having its 85 lower open end extending into the fuel within the well and its upper end constructed to form a slow speed nozzle 11. The slow speed nozzle is positioned within a chamber 12 into which extends one end of a slow 90 speed emulsion conduit 13, 14 opening through the wall of the suction pipe 4 adjacent the throttle valve 9, and having a branch 15 leading to my improved regulat- 95 ing device R to be described in detail hereinafter. The chamber 12 has air openings 16 formed therein which are made small enough so as not to be sufficient to maintain atmospheric pressure in the interior. In this form of my invention the slow speed 100

nozzle is above the fuel level within the atmospheric well as disclosed in my Patent 1,188,390, before referred to, and as shown in detail in the slightly modified construction of Figures 3 and 4.

- In the form of my invention diagrammatically illustrated in Figure 2, in which figure parts corresponding to parts already described are indicated by the same reference characters with a prime affixed thereto, the slow speed emulsion conduit 13', 14' has at its lower end, below the normal fuel level, a calibrated opening 17 forming a determined supply for idling or slow speed running. Within the branch 15' there is a needle valve 18 having a seat 19 formed in the branch 15' of the conduit intermediate its point of union with the main conduit and the regulating device R'. This needle valve controls the maximum amount of air which can pass into the branch 14 even though the device R' is in wide open position, as will be clearly pointed out herein-after.
- 25 A commercial embodiment of the diagrammatic construction of Figure 1 is illustrated in Figures 3 and 4 in which the tube 10 is screwed into the lower end of the casing 12 carried by a plug 20 screwed into an 30 enlarged chamber 21 formed in the upper end of the atmospheric well and communicating by the branch conduit 14 with the suction pipe 4. The portion of the conduit 13, as disclosed in Figure 1, which extends into the casing 12, is in the form of a tube 22 vertically adjustable within the casing 12, and communicating through openings 23 in said tube, and openings 23' in the plug 20 with the conduit 14.
- 35 40 The upper end of the chamber 21 is closed by a screw-threaded plug 24 having a tubular upwardly projecting portion 25 communicating with the interior of the chamber 21 through an opening 26. Around the tubular portion 25 is a split bracket 27 clamped in position by a tightening screw 28 and held against removal by engaging a shoulder 29 on the tubular portion 25.
- 45 50 Slidably mounted within the tubular portion 25 is a needle valve 30 adapted to control the opening 26 to the chamber 21. Surrounding the needle valve 30 is a compression spring 31 partially enclosed by a hollow head 32 secured to the needle valve and provided with openings 33 to the atmosphere. For moving the needle valve 30 against the action of the spring 31 to close the opening 26, there is provided a cam 34 mounted on the shaft 35 in the bracket 27 and adapted to be operated by a lever 36. The open position of the needle valve 30 is controlled by an adjustable stop screw 37 adapted to engage a stop 38 formed by the bracket 27, and thereby regulate the maxi-

55 mum amount of air which will pass the needle valve 30 when this valve is in open position.

In adjusting the carburetor for use, the stop screw 37 is moved until the proper amount of air is permitted to pass through the opening 26 to produce an accurately proportioned mixture for idling or slow running speeds when the motor has reached its normal working temperature. In starting, or when the engine is cold, the supply of air through the opening 26 is entirely cut off or partly diminished to enrich the slow speed mixture to facilitate starting. This is accomplished by the action of the cam 34 on the needle valve 30. It will be apparent that this is accomplished without changing the main air supply to the atmospheric well 6, so that the adjustment of the compensating nozzle is not destroyed or altered.

55 60 In Figures 5, 6 and 8, there is illustrated a commercial embodiment of the diagrammatic construction illustrated in Figure 2, with the needle valve 18 replaced by the stop screw before described, in connection with Figures 3 and 4. In these figures of the drawings, parts corresponding to parts already described are represented by the same reference characters primed as in Figure 2. As so constructed, the conduit 13' is carried by a plug 24' held in position by a set screw 40 and carrying a regulating device R', as previously described in detail. The plug 24' has an opening 23' formed therein and communicating with the conduit 14' leading to the throttle valve. The operation of this type of control is the same as that illustrated in Figures 1, 3 and 4 of the drawings and need not be described in detail.

65 70 The advantages of the present invention arise from the provision of means for easily and quickly enriching the slow speed mixture without changing the air supply to the atmospheric well.

75 I claim:

1. In a carburetor, a constant level chamber, a suction pipe having a fuel nozzle therein communicating with said chamber, a throttle valve in said pipe, an atmospheric well open to the atmosphere, a conduit extending from the well and opening into the suction pipe adjacent the throttle and constituting a slow speed feed device, means for feeding an emulsion of fuel and air from the well to the conduit, regulable means set in an open position for determining the maximum supply of air to the conduit, and means for temporarily decreasing the supply of air to the conduit without effecting the air supply to the well, substantially as described.
